US00D894163S

(12) **United States Design Patent** (10) **Patent No.:** **US D894,163 S**
(45) **Date of Patent:** ** *Aug. 25, 2020

(54) **ELECTRONIC DEVICE**

- (71) Applicant: **Samsung Electronics Co., Ltd.**, Suwon-si (KR)
- (72) Inventors: **Sungkwon Kim**, Seoul (KR); **Kwanue Hong**, Yongin-si (KR); **Chungha Kim**, Seoul (KR); **Giha Woo**, Seoul (KR)
- (73) Assignee: **Samsung Electronics Co., Ltd.**, Suwon-si (KR)
- (*) Notice: This patent is subject to a terminal disclaimer.

(**) Term: **15 Years**

(21) Appl. No.: **29/650,474**

(22) Filed: **Jun. 7, 2018**

CLAIM

We claim the ornamental design for an electronic device, as shown and described.

DESCRIPTION

FIG. 1 is a front perspective view of an electronic device showing our new design;

FIG. 2 is a front view thereof;

FIG. 3 is a rear view thereof;

FIG. 4 is a left-side view thereof;

FIG. 5 is a right-side view thereof;

FIG. 6 is a top view thereof;

FIG. 7 is a bottom view thereof;

FIG. 8 is an enlarged view of the encircled portion in FIG. 4;

FIG. 9 is an enlarged view of the encircled portion in FIG. 5;

FIG. 10 is an enlarged view of the encircled portion in FIG. 6; and,

FIG. 11 is an enlarged view of the encircled portion in FIG. 7.

The evenly-dashed broken lines shown in the drawings depict portions of the electronic device that form no part of the claimed design. The dot-dashed broken lines encircling portions of the claimed design that are shown in enlargements form no part of the claimed design.
